(57) **CLAIM**

The ornamental design for an educational illustration machine, as shown and described.

DESCRIPTION

FIG. 1 is a front view of an educational illustration machine showing our new design;

FIG. 2 is a rear view thereof;

FIG. 3 is a left side view thereof;

FIG. 4 is a right side view thereof;

FIG. 5 is top view thereof;

FIG. 6 is a bottom view thereof;

FIG. 7 is a top view thereof, showing our design with the display panel in an open position;

FIG. 8 is a right side view thereof, showing our design with the display panel in a closed position, our design being supported in a standing position by a hinged leg; and,

FIG. 9 is a view similar to FIG. 8 but with the display panel shown in an open position.
